(57) **CLAIM**

The ornamental design for a "hands-free" mobile phone docking station and speakerphone, as shown and described.

DESCRIPTION

FIG. 1 is a front elevational view of a "hands-free" mobile phone docking station and speakerphone;
 FIG. 2 is a rear elevational view thereof;
 FIG. 3 is a left side elevational view thereof;
 FIG. 4 is a right side elevational view thereof;
 FIG. 5 is a top plan view thereof;
 FIG. 6 is a left side elevational view showing the support base in a folded down position; and,
 FIG. 7 is a left side elevational view showing the plug in an extended position.
